Primary Examiner — Cathron C Brooks*Assistant Examiner* — Christian P. McLean(74) *Attorney, Agent, or Firm* — Young Basile Hanlon & MacFarlane, P.C.(57) **CLAIM**

The ornamental design for a liquid beverage container, as shown and described.

DESCRIPTION

FIG. 1 is a front perspective view of a liquid beverage container;

FIG. 2 is a front view of the liquid beverage container of FIG. 1;

FIG. 3 is a rear view of the liquid beverage container of FIG. 1;

FIG. 4 is a left side view of the liquid beverage container of FIG. 1;

FIG. 5 is a right side view of the liquid beverage container of FIG. 1; and,

FIG. 6 is a top elevational view of the liquid beverage container of FIG. 1.

The shade lines show contour and not surface ornamentation.

1 Claim, 6 Drawing Sheets(56)
